UNITED STATES PATENT OFFICE

105,640

DESIGN FOR A SLIP

Julia Lutfy Sarge, New York, N. Y.

Application June 15, 1937, Serial No. 69,849

Term of patent 3½ years

To all whom it may concern:

Be it known that I, Julia Lutfy Sarge, a citizen of the United States of America, residing in Manhattan, county of New York, and State of New York, have invented a new, original, and ornamental Design for a Slip, of which the following is a specification, reference being had to the accompanying drawing, forming part thereof, wherein,

The characteristic feature of my design resides in the hemstitched ornamentations on the top of the slip as shown.

I claim:

The ornamental design for a slip, substantially as shown, and described.

JULIA LUTFY SARGE.
